US00D556176S

(12) **United States Design Patent** (10) **Patent No.:** **US D556,176 S**
(45) **Date of Patent:** **** Nov. 27, 2007**

(54) **PORTABLE PHONE**

(75) Inventors: **Jin Nam Kim**, Seoul (KR); **Hyun Seop Kim**, Seoul (KR); **Chang-Hwan Hwang**, Goyang-Si (KR)

(73) Assignee: **Samsung Electronics Co., Ltd.**, Suwon-Si (KR)

(**) Term: **14 Years**

(21) Appl. No.: **29/270,036**

(22) Filed: **Dec. 14, 2006**

(30) **Foreign Application Priority Data**

Aug. 16, 2006 (KR) 30-2006-0033654

(51) **LOC (8) Cl.** **14-03**

(52) **U.S. Cl.** **D14/138**

(58) **Field of Classification Search** D14/137-138, D14/147-148, 156, 218, 247-248, 341-347, D14/496; D16/208; D21/329, 331, 333, D21/517; 348/14.01-14.02; 361/814; 379/ 433.01-433.13; 455/556.1-556.2, 575.1, 455/575.3, 575.4, 566, 90.3

See application file for complete search history.
